W. E. WREAD

LOCK

Filed Sept. 8, 1925

UNITED STATES PATENT OFFICE.

WILLIAM E. WREAD, OF LOS ANGELES, CALIFORNIA, ASSIGNOR, BY MESNE ASSIGNMENTS, TO WREAD PRODUCTS CORPORATION, A CORPORATION OF CALIFORNIA.

LOCK.

Application filed September 8, 1925. Serial No. 54,965.

The lock is particularly applicable to front doors, and comprises thumb latch means, and key and knob operated means to retract a single draw bolt.

5 It is preferable in so called front door locks to provide the door on the outside with a handle, thumb latch draw bolt retracting means and key operated draw bolt retracting means; and on the inside with knob operated draw bolt retracting means.

An object of my invention is to provide a novel lock of this character the draw bolt of which may be independently retracted either by a knob, a key, or a thumb latch.

15 An object is to provide a novel lock of this character in which each one of the draw bolt retracting means is operable, irrespective of whether or not the other retracting means are rigidly held in normal position.

20 Another object is to provide a novel lock of this character, in which one or all of the draw bolt retracting means may be securely locked from the inside of the door.

A further object is to provide a novel lock 25 of this character in which the thumb latch means may be locked from the inside of the door and still permit retraction of the draw bolt by operation of either the knob or key operated retracting means.

30 Further objects are to provide a lock which is simple in construction, inexpensive to manufacture, and efficient in operation.

Advantages of my invention are to provide 35 a lock, the body of which may be formed in a single casting, and which may be quickly and easily installed in a door.

This application includes certain novel features more particularly shown and described in my copending application filed 40 August 31, 1925, Serial Number 63,548; and may be said to apply the key and knob operated lock shown in said application to a front door.

Other objects, advantages and features of 45 invention may appear from the accompanying drawing, the subjoined detailed description and the appended claims.

The accompanying drawing illustrates the invention.

50 Figure 1 is a side elevation of my novel lock as viewed from the inside of a door a fragment of which is shown. Parts are broken away to show the draw bolt latching finger.

55 Fig. 2 is a fragmentary end view of my

lock looking from the right of Fig. 1. Parts are broken away to show interior construction and to contract the view.

Fig. 3 is an enlarged fragmentary longitudinal sectional view of my lock on irregular line x^3-x^3 , Fig. 4.

Fig. 4 is a sectional view on line x^4 , Fig. 3 and on the same scale as Fig. 3. Dotted lines indicate the draw bolt and thumb latch means in draw bolt retracting position.

65 Fig. 5 is a fragmentary sectional view of my lock showing the draw bolt retracted by the key operated retracting member.

Fig. 6 is a fragmentary sectional view on line x^5 , Fig. 4.

70 Fig. 7 is a fragmentary sectional view on line x^6 , Fig. 4, the door being omitted.

Fig. 8 is a detail side elevation of the draw bolt locking bolt.

75 Fig. 9 is a detail plan view of the locking bolt shown in Fig. 8.

Fig. 10 is an end view of the key operated draw bolt retracting member.

To prepare the door or the like A, to receive my novel lock I provide the same with 80 a transverse bore B, and with a bore C that extends from the bore B, at right angles to the axis thereof, to the free or outer edge D of the door, and a recess E which depends from, and communicates with, the bore B, and extends vertically in such door at right angles to the axis of the bore C.

85 My invention comprises a tubular lock body 1 which is mounted in the bore B and said body 1 has an externally threaded extension 2 on one side thereof. The extension 2 is preferably cast integral with the body 1 but it is understood that the same may be a separate part as more clearly set forth in my above referred to copending application.

90 Thumb latch supporting means in the form of a tube 3 depends from the body 1 and is adapted to be received in the recess E. The tube 3 may be threaded to the body 1 or it may be preferable to die cast the tube 3 integral with the lock body 1 and extension 2.

95 A draw bolt 4 is provided at its inner end with a crosshead 4' and said draw bolt includes a sleeve 5 which extends toward the free edge D of the door and is journaled in an orifice 5' formed in the body 1. The crosshead 4' and sleeve 5 is provided with a bore 6 in which a pin 7 is adapted to slidably fit. The pin 7 is provided with a re-

70

95

105

110

- duced end 7' that extends through the body 1 and is riveted over at its outer end to secure the pin to the body 1. The pin 7 serves to support the draw bolt 4 and acts as a guide for the same. A compression spring 8 surrounds the pin 7 and operates between the crosshead 4' and lock body and tends to normally hold the draw bolt in latching position.
- 10 The draw bolt also includes a latch member 9 that is formed with a threaded shank 10 which is threaded into the sleeve 5 a predetermined distance so that the latch member extends from the free edge of the door 15 a sufficient distance. A guide plug 11 is driven into the outer end of the bore C flush with the edge D to close said bore, and said plug is provided with an opening 12 in which the latch member 9 is adapted to slide.
- 20 The outer periphery of the plug 11 is serrated as at 13, so that the plug 12 will not accidentally protrude beyond the free edge D of the door.
- Knob operated draw bolt retracting means 25 14 is provided to retract the draw bolt from the inside of the door and such means comprises a disc 15 formed on the inner end of an oscillating shaft 16 which extends from the disc 15 and is journalled in the extension 2. The disc 15 is mounted between the closed end of the lock body 1 and the crosshead 4' and is of sufficient thickness to fill the space therebetween so that end play of the shaft 16 is practically eliminated.
- 35 The outer end of the shaft 16 may be reduced in diameter if desired and is threaded as at 17 to receive a handle 18 which bears against the shoulder 19 formed by reducing the outer end of shaft 16.
- 40 An arcuate lug 20 formed on the disc 15 projects inwardly therefrom and the crosshead 4' rests against both ends of said lug under pressure of the spring 8. As the shaft 16 is oscillated either to the right or left by the handle 18 one end of the lug 20 will force the crosshead 4' against the tension of spring 8 and thereby retract the draw bolt 4.
- Key operated draw bolt retracting means 50 is provided to retract the draw bolt from the outside of the door and comprise a cylindrical key lock 21 which is screwed into the body 1 in axial alignment with the shaft 16. A disc 22 having an arcuate lug 23 similar to disc 15 and lug 20 is secured to the key 55 operated tumbler 21' of the lock 21.
- The ends of the lug 23 rest against the crosshead 4' in the same manner as before described in connection with the lug 20. When the tumbler 21' is oscillated the draw bolt 4 will be retracted, irrespective of whether or not the handle 18 is rigidly held.
- 60 A cover plate 24 is secured to the inside of the door by any suitable means, such as screws 25, and the shaft 16 extends therethrough. A clamp nut 26 is threaded onto the extension 2 and has a shoulder 26' that bears against the plate 24.
- An outside cover plate 27 is secured to the outside of the door A by any suitable means such as screws 28 and is provided with an orifice 27' through which the key lock 21 protrudes. A sleeve 29 threaded onto said lock bears against the plate 27 and clamps the door between the shoulder 26' and the inner end of said sleeve 29 and thus positions and firmly holds the lock body 1 in the bore B.
- A bolt 30 threaded into the plate 27 extends through the tube 3 adjacent the lower end thereof and nuts 30' threaded to said bolt 30 on opposite sides of the tube 3 serve to position and hold the tube in rigid position. A suitable handle 31 of any desirable contour or shape by means of which the door may be swung is secured to the plate 27 by a nut 31'.
- Thumb latch draw bolt retracting means are provided to retract the draw bolt irrespective of the knob or key operated retracting means and comprise a thumb piece 32 pivotally mounted between ears 33 formed on the inner side of plate 27, a stem 34 that extends inwardly from the thumb piece 32 into a slot 35 formed in the tube 3. A wedge block 36 is slidably mounted in the tube 3, and rests by gravity against the stem 34. A filler plate F is secured to the tube 3 by rivets G and forms a bearing block against which the wedge block 36 slides.
- The upper surface of the block 36 is inclined at an angle as at 37, Fig. 4, the purpose of which will be further described.
- A finger 38 is pivotally mounted in the tube 3 on a pin 39 which extends through the tube 3 and is riveted thereto. The upper end of the finger 38 engages the crosshead 4', while the lower end thereof is provided with a roller 40 which rests against the surface 37. Spacing members H retain the finger 38 in a central position in the tube 3.
- When the thumb piece 32 is depressed the stem 34 will move the block 36 upwardly and the surface 37 will engage the roller 40 and force the finger 38 to move to the dotted line position shown in Fig. 4 and thus retract the draw bolt 4.
- The thumb piece will operate to actuate the cross head member entirely independently of the knob 18 or key lock 21.
- If desired the thumb latch retracting means may be locked from the inside of the door, against operation, by means of a locking pin 41, which is journalled in the tube 3, and projects through the plate 24.
- One end of the pin 41 is provided with a head a to prevent withdrawal of the pin 41 and the other end of the pin 41 is flattened as at b to receive a finger 42 which has a sliding fit with said flattened end. The finger 42 is rotatably mounted in plate 24 and

is secured thereon by a collar *n* which has a drive fit on a shank *o* formed on the finger 42, and provides means whereby said pin 41 may be rotated.

5 A recess 43 is provided in the pin 41 to receive the finger 38 when the finger 38 is moved to retract the draw bolt. By rotating the pin 41 to move the recess 43 away from the finger 38, the solid portion of the 10 pin 41 is moved into the path of the finger 38 and will prevent movement of the finger on its pivot. The pin 41 it will be noted only controls the operation of the thumb latch retracting means and the draw bolt may be 15 retracted by either the knob or key operated retracting means.

However, I also provide means controlled from the inside of the door whereby the draw bolt may be locked against operation 20 by any of the hereinbefore mentioned retracting means, and such locking means comprise a lock bolt 44 journaled in the body 1 adjacent to and extending through a portion of the sleeve 5. The lock bolt 44 is identical 25 to that shown in my copending application and is provided at one end with a head *d* to prevent withdrawal and at its other end with a flattened portion *e* that extends through the plate 24 and is adapted to slid- 30 ingly receive a finger 45 which provides means whereby the lock bolt 44 may be rotated. The finger 45 is identical in construction and assembly to the finger 42. The sleeve 5 is provided with a transverse notch 35 46 into which the pin 44 is adapted to be rotated to thereby prevent retraction of the draw bolt.

The lock bolt 44 is provided with a recess 47 which is adapted to normally accommo- 40 date the sleeve 5 and permit free movement of the sleeve therethrough.

By rotating the lock bolt 44 to bring the recess 47 out of alignment with the sleeve 5, the body of said pin is presented to said 45 sleeve and enters the notch 46 in said sleeve to lock the same as described.

The operation and assembly of my invention will be apparent from the foregoing description.

50 I claim.

1. A lock comprising a lock body, a draw bolt slidably mounted in said body, a knob mounted on said body; means operably connecting said knob and said draw bolt to retract said draw bolt; a key lock mounted on said body; means connecting said key lock and said draw bolt to retract said draw bolt; a thumb latch; means connecting said thumb latch and said draw bolt to retract said draw bolt, said knob operated draw bolt retracting means, key operated draw bolt retracting means and thumb latch operated draw bolt retracting means each being independently operable to retract said draw bolt irrespective of the other retracting means.

2. A lock comprising a lock body, a draw bolt slidably mounted in said body and having a cross head in its inner end; a thumb piece; a finger one end of which is in engagement with said cross head; and means connecting said thumb piece and the other end of said finger whereby said finger may be moved on its pivot to retract said draw bolt. 70

3. A lock comprising a lock body, a draw bolt slidably mounted in said body and having a cross head on its inner end; a thumb piece, a finger one end of which is in engagement with said cross head; a wedge block engaging the other end of said finger and said thumb latch; said finger, wedge block and thumb piece being so adapted and arranged that operation of said thumb piece will retract said draw bolt. 75

4. A lock comprising a lock body, a draw bolt slidably mounted in said body and having a cross head on its inner end; a thumb piece; a pivotally mounted finger one end of which engages said cross head; means whereby said finger may be moved on its pivot to retract said draw bolt; and means adapted to lock said finger against draw bolt retracting movement. 80 90

5. A lock for a door or the like comprising a lock body mounted in said door; a member depending from said lock body; a draw bolt slidably mounted in said body and provided with a cross head; a finger in said member, the upper end of said finger engaging said cross head; a pin in said member on which said finger is pivoted; a cover plate secured to the door; a thumb piece pivoted to said plate; a wedge block in said member resting on said thumb piece and engaging said finger; operation of said thumb piece being adapted to raise said wedge block and move said finger to retract said draw bolt. 95 100 105

6. A lock for a door or the like comprising a lock body mounted in said door; a tube depending from said body; a draw bolt slidably mounted in said body and provided with a cross head; a finger in said tube, the upper end of said finger engaging said cross head member; a pin in said tube on which said finger is pivoted; a cover plate secured to the door; a thumb piece pivoted to said plate; a wedge block in said tube resting on said thumb piece and engaging said finger, said thumb piece being adapted to raise said wedge block and move said finger to retract said draw bolt, a locking pin in said tube and projecting from one side of the door; a finger on the projecting end of said locking pin, and said locking pin being adapted to be rotated into engagement with said finger to prevent retracting movement of the finger. 110 115 120 125

7. A lock comprising a lock body, a draw bolt slidably mounted in said body and having a crosshead; a thumb piece; a pivot- 130

ally mounted finger; one end of said finger engaging said cross head connecting said thumb piece and said finger whereby said finger may be moved to retract said draw bolt; a retracting member mounted in said body; a knob secured to said retracting member; and means operatively connecting said cross head and said retracting member, whereby rotation of said knob will retract said draw bolt independently of the thumb operated retracting means.

8. A lock comprising a lock body, a draw bolt slidably mounted in said body and having a cross head; a thumb piece; a pivotally mounted finger; one end of said finger engaging said cross head connecting said thumb piece and said finger whereby said finger may be moved to retract said draw bolt; a key lock mounted in said body, an arcuate lug formed on said lock and operatively connecting said key lock and said cross head whereby operation of said key lock will retract said draw bolt independently of the thumb operated retracting means.

9. A lock comprising a lock body, a draw bolt slidably mounted in said body and having a crosshead; a thumb piece; a pivotally mounted finger, one end of said finger engaging said cross head; a sliding lock connecting said thumb piece and said finger whereby said finger may be moved on its pivot to said draw bolt; a retracting member mounted in said body; a knob secured to said retracting member; an arcuate lug on said draw bolt for operatively connecting said cross head and said retracting member whereby rotation of said retracting member will retract said draw bolt independently of the thumb piece operated

means; a key lock mounted in said body and an arcuate lug on said lock operatively connecting said key lock and said cross head whereby rotation of said key lock will retract said draw bolt independently of the thumb piece operated means.

10. A lock comprising a lock body, a draw bolt slidably mounted in said body and having a cross head; a thumb piece; a pivotally mounted finger, one end of said finger engaging said cross head connecting said thumb piece and said finger whereby said finger may be moved to retract said cross head and selectively engaging said finger to lock said finger against movement; and independent locking means selectively engaging said draw bolt.

11. A lock comprising a lock body, a draw bolt having a crosshead slidably mounted in said body; a retracting member comprising a disc, a lug on said disc adapted to engage said crosshead and retract said draw bolt upon rotating said retracting member; a key lock mounted in said lock body; a disc on said key lock; a lug on said last mentioned disc adapted to engage said crosshead and retract said draw bolt on rotation of said key lock; a tube depending from said body; a finger pivotally mounted in said tube, one end of said finger engaging said crosshead; a thumb piece; and a sliding block operatively connecting said thumb piece and said finger whereby depression of said thumb piece is adapted to move said finger to retract said draw bolt.

In testimony whereof, I have hereunto set my hand at Los Angeles, California, this 1st day of September, 1925.

WILLIAM E. WREAD.
